UNITED STATES PATENT OFFICE

WILLIAM G. LANG, OF WASHINGTON, DISTRICT OF COLUMBIA

SAFETY ATTACHMENT FOR PUNCH PRESSES

Application filed March 1, 1929. Serial No. 343,798.

This invention relates to safety means for clutches in power presses, punches and similar machines.

In certain types of presses and punches the operator places work in the press and operates a pedal to start the press. The pedal throws in a clutch which connects a driving with a driven part of the machine to cause the press or punch to make one cycle of operation, whereupon the clutch is operated to disconnect the press from the source of power. So long as the clutch remains intact these machines operate with safety to the operator. If, however, the key element in the clutch becomes broken the means which releases the clutch fails to function to disconnect the driving and driven elements of the machine. This frequently happens and not infrequently, also, the operator thinking the machine is stopped puts his hands beneath the press to put an additional piece of work in position, with the result that his hand is caught beneath the press and seriously injured.

The device forming the subject matter of this invention seeks to safeguard presses in this respect, by providing a safety device which will stop the machine in case the clutch key becomes broken. So long as this key is uninjured the machine will operate in safety without my device playing any part in the operation. As soon, however, as the key is broken, the mechanism which normally releases the key to disconnect the driving and driven mechanism fails to function. My device then automatically comes into play to stop the press.

In presses of the kind just described the operator sometimes fails to release the pedal after pressing it down. This causes the machine to make more than one stroke. A further safety feature consists in mechanism which will stop the machine even if the operator keeps his foot on the pedal.

Referring to the accompanying drawings which are made a part hereof, and on which similar reference characters indicate similar parts,

Figure 1 is a front elevation of a press having my safety device applied thereto,

Figure 2 is a side elevation with the main flywheel and certain other parts removed, as seen substantially on line 2-2 of Fig. 1,

Figure 3 is an enlarged sectional view, showing the clutch key in locked position, 55

Figure 4 is a section on line 4-4 of Fig. 3,

Figure 5 is a detached view of one of the safety devices,

Figure 6 is a perspective view of the safety cam, 60

Figure 7 is a perspective view of the clutch key,

Figure 8 is a detail view of the clutch releasing means, and

Figure 9 is a detail plan view of the element shown in Figure 8.

Referring to the drawings, reference character 10 indicates the supporting legs of a press having an off-set bent over arm 11 which carries a motor 12 supported on brackets 13. The upper end of the standard 11 is provided with bearings 14 and 15 in which a crank shaft 16 is mounted. The crank shaft has a driving pulley 17 loosely mounted on its outer end. A belt 18 provides driving connection between the motor 12 and the pulley 17. A crank pin 19 on the shaft 16 is connected to a reciprocating punch shaft 20 carrying on its lower end a punch 21 which co-operates with an anvil 22. The drive wheel 17 is locked to the driven shaft 16 by means of a key 23 which slides in a slot 24 in the shaft 16. The key 23 engages a slot 25 in the side of the drive wheel 17. Hardened plugs 26 are pressed into holes in the drive wheel and cut off at 27 to provide a hardened surface against which the key 23 engages. The key 23 is urged into locking position by means of a spring 28 seated in a bore in the key. The spring surrounds and is preferably guided by means of a short rod 30 which is secured by a pin 29 to the shaft 16. The key 23 has on one side a notch 31. One side of the notch is cut to provide a cam surface 32, which surface is engaged by a releasing dog which withdraws the key from locking connection with the drive wheel, as will be more fully described. The shaft 16 has an enlarged collar 33 which is engaged by a brake drum 34 which drum is 95

100

kept normally tight enough to allow the shaft 16 to rotate when driven by the fly wheel 17, but which will immediately stop the shaft when the shaft is disconnected from the driving wheel. Each rotation of the fly wheel 17 causes the punch to make one cycle of operation. With each cycle the key is withdrawn from locking connection with the fly wheel 17. The means for withdrawing the key will now be described. Pivoted on the frame of the machine at 35 is a lever 36. This lever has on its outer end a beveled edge 37 which engages the cam edge 32 on the key 23 to withdraw the key when the lever is in its uppermost position. A compression spring 38 surrounding a guide rod 39 secured to the lever 36 normally urges the lever upward. The rod 39 is guided through a hole in a bracket 40 secured upon the standard 11. The outer end of the lever 36 has a depending notched portion 41 by means of which the lever is pulled down against the tension of the spring 38. A rod 42 is slidably mounted between guideways 43 and 44 secured to the frame work of the machine. A latch 42' is pivoted to this rod. This latch 42' has its upper end notched at 45 to provide a hook for engagement with the notch 41 on the lever 36. A block 46 is secured to the end of the latch 42' by means of a bolt or screw 47, the upper end of the block 46 extending up beyond the center of the shaft 16. This block is held in engagement with the periphery of the shaft by means of a tension spring 48. A lever 49 is pivotally secured to the frame of the machine at 50 and is pivoted at 51 to the block 42. A rod 52 is hooked in the outer end of the lever 49 and connected to a foot treadle 53. A tension spring 54 tends to hold the foot treadle 53 in an elevated position. A block 61 is secured to the latch 42' just beneath the end of the lever 36. The purpose of this is to enable the latch 42' to lift the end of the lever 36 in case the spring 38 fails to operate. When the operator wishes to start operation of the machine he presses down upon the pedal 53. This pulls down the bar 42 and latch 42' and by means of the notches 45 and 41 pulls down the lever 36 to withdraw the edge 37 from engagement with the cam edge 32 of the key 23. As the drive wheel rotates to bring either of the slots 25 opposite the end of the key, the key is driven into the notch to key the shaft and drive wheel together to rotate the shaft to operate the punch. As the key again reaches the edge 37 of the lever 36 this edge acts as a dog to withdraw the key from engagement with the drive wheel and stops rotation of the shaft 16.

In operation, the operator presses the pedal 53 as just described. This causes the press to make one operation. In presses as formerly constructed, should the operator keep his foot on the pedal, the press would con-

tinue to operate, and if the operator inadvertently put his hand beneath the punch, forgetting that he had his foot on the pedal, his hand might be injured.

How the structure just described will prevent the machine from operating even if the operator continues to hold down the pedal 53 will now be explained: The block 46 just described is held in contact with the shaft 16 riding in an annular channel 56 on the shaft. As the key 23 reaches the position representing about three fourths of a revolution from the starting point shown in Fig. 2, it strikes the bar 46 which pushes the latch 42' to cause the notch 45 to release the notch 41 and allow the lever 36 to move upward to the position where it will engage the key 23 when the shaft has rotated another quarter revolution. The operator may continue to hold the pedal down without endangering himself. It will be seen therefore that my device will cause the press to make only one operation unless the operator definitely presses the pedal to cause a second operation.

The impact which the keys 23 have to receive in starting the machine subjects them to enormously heavy duty. Due to crystallization of the metal or to metal fatigue or other causes, these impacts sometimes break the keys. When this happens the spring 28 pushes the broken off end of the key into the notch to connect the driving wheel with the shaft 16. Moreover, the releasing dog 37 under these circumstances does not operate to withdraw the key at each rotation of the shaft 16. A broken key therefore not infrequently causes the punch to be driven down to catch the hand of the operator to injure him. Means for withdrawing the key when it has become broken will now be described: Positioned in axial bores in the hub of the drive wheel 17 are pins 57 and 58. A cap 59 is screw threaded on the outer end of the shaft 16. This cap is secured against rotation by means of a screw 60 which is threaded in a bore cut partly in the cap 59 and partly in the screw threaded end of the shaft 16. A plate 62 is fastened to a depending bar 63 which bar is secured to a bracket 64. The plate 62 is provided with a slot 65 having plates 66 and 67 secured on each side in order to support a cam 68. A rod 69 has its upper end positioned in a hole in the cam 68 and is secured at its other end by means of a bracket 70 to the rod 52. A plate 71 is secured by means of a screw 72 to the cam 68 which plate holds the end of the rod 69 in position in the cam 68. The forward edge of the inner end of the cam 68 is cut to provide a wedge shaped surface 73. The operation of the structure just defined is as follows: As the fly wheel 17 rotates and one of the pins 57 or 58 is brought to the lowermost position, its outer end rides over the wedge edge 73 on the inner end of the cam 68. This wedge edge 123

moves the pin axially to push out the key 23 from the slot 25 in the opposite edge of the pulley 17. If therefore the key has been broken so that the dog 37 will not withdraw it when it reaches the lowermost position, the inner end of the key will be pushed out by means of the cam 68 acting against the end of the rod 57 or 58, so that the punch or press will be stopped in the elevated position. The rods 57 and 58 cannot possibly fail to push out the key, since it is impossible for the pulley 17 to rotate without the end of the rod 57 or 58 riding the cam edge 73.

In order to prevent operation of the press when the operator's hand is beneath the press, I have provided safety means as follows: Bars 74 are pivotally mounted on brackets 75. Secured at the outer ends of the bars 74 are depending rods 55. These rods are secured in a ring plate 76. A compression spring 77 is positioned between the upper end of the plate 76 and the bracket 75. A rod 78 is rigidly secured to the bars 74 and has on its outer end a rock arm 79. This rock arm is connected by means of a rod 80 and a bracket 81 to the rod 52. When the pedal 53 is pressed down it carries with it the rod 52 and the rod 80 to swing the rock arm 79 to swing the disc 76 to the position which the work assumes. If the operator's hand should be placed on the anvil 22, the disc 76 will strike his hand so that the pedal 53 cannot be pushed down sufficiently far to pull down the dog 37 so as to release the key 23.

It will clearly be seen therefore that whenever the operator's hand is in the position in which it might be injured by the punch or press, he cannot start the press.

It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention, what I claim as new and desire to secure by Letters Patent, is:

1. In a power press having a driving and a driven element, a slidable key for connecting the driving with the driven element, means for sliding said key axially to disconnect the driving from the driven element at the completion of each revolution, and means operable upon a breaking of said key to disconnect the driving from the driven element, substantially as set forth.

2. In a power press having a driving and a driven element, means for clutching the driving element to the driven element comprising a key in said driven element, means for axially moving said key at a predetermined period in each cycle of the press to disconnect the driving and the driven elements, and means in said driving element op-

erable only upon a breaking of said key to axially move said key to disconnect the driving from the driven element, substantially as set forth.

3. In a power press having a driving and a driven element, clutch mechanism for connecting the driving with the driven element comprising a key in said driven element slidable axially to connect the driving with the driven element, means operable at a predetermined position of the driven element to move the key axially to disconnect the driving and driven elements, and means in said driving element operable to move the said key axially in case the said last named means fails to function, substantially as set forth.

4. In a power press having a driving and a driven element, an axially movable key mounted in said driven element for connecting the driving with the driven element, plungers in the driving element, a manually controlled cam operable at a predetermined radial position of the plungers to move one of the plungers axially to disconnect the said key from the driving element in case this key is broken or otherwise fails to function, substantially as set forth.

5. In a power press having a driving and a driven element, a clutch key for connecting the driving with the driven element, means for releasing said key to connect the driving and the driven element comprising a horizontally disposed bar pivoted at one end and having a cam surface at the opposite end adapted to coat with said key, a hook adjacent said cam, a vertically disposed bar pivoted at its lower end and having its upper end in the path of movement of said key, a hook on said vertical bar adapted to coat with said hook on said horizontal bar, and manually operated means to disengage said cam from said key to permit the release of said key and rotation of said driven element by said driving element until said cam is released to re-engage said key by contact of said key with said vertical lever, substantially as set forth.

6. In a press having a driving and a driven element and a key positioned in the driven element and adapted to engage the driving element for keying the two together and having means for normally disengaging said key, auxiliary means operable automatically to push the said engaging means out of engagement with the driving element when the said engaging means becomes broken so as normally to fail to be withdrawn at a predetermined time, substantially as set forth.

In witness whereof, I have hereunto set my hand at Washington, District of Columbia, this 27th day of February, A. D. nineteen hundred and twenty-nine.

WILLIAM G. LANG.
